(57) **CLAIM**

The ornamental design for a container for dry products, as shown and described.

DESCRIPTION

FIG. 1 is a top, front, left side perspective view of the container for dry products, showing our new design; FIG. 2 is a bottom, front, right side perspective view thereof; FIG. 3 is a front elevation view thereof; FIG. 4 is a rear elevation view thereof; FIG. 5 is a top plan view thereof; FIG. 6 is a bottom plan view thereof; FIG. 7 is a left side elevation view thereof; and, FIG. 8 is a right side elevation view thereof.

The broken lines consisting of evenly spaced dash lines in the drawings depict parts of the container for dry products that form no part of the claimed design. The broken lines consisting of dash-dot-dot lines in the drawings depict the boundary of the claimed invention and it is understood that the claim extends to the boundary that forms no part of the claimed design.
